FRANK B. STEARNS, OF SHAKER HEIGHTS VILLAGE, OHIO.

FLUID COMPRESSOR.

Application filed May 24, 1924. Serial No. 715,538.

This invention relates to fluid compressors.

The primary requisites in obtaining the best mechanical and volumetric efficiency of compressors is to provide inlet and outlet 5 ports for the compression chamber which are of an area capable of handling a volume of fluid equal to the capacity of the compression chamber, and to provide valve mechanism for controlling the ports which will operate proportionately to the speed at which the compressor element operates. It therefore follows that the area of the ports in large volume compressors are larger than in small volume compressors, and that the valve 15 mechanism operates more rapidly in high speed compressors than in low speed compressors. So far as I am now aware, prior compressors are incapable of efficiently handling a large volume of fluid at high speed, 20 for various reasons, among which are the necessity of employing large valves of such type and so operated that they will not withstand the rapid movement at which they must be operated without quickly becoming 25 distorted or broken.

There are many instances where a compressor having a large volume and high speed can be used, and for illustration, I have shown and described such a compressor used 30 with a self igniting engine for supplying compressed air to the engine cylinder for scavenging after explosion and also supplying precompressed air thereto.

An object of my invention is to provide 35 a compressor which will supply a large volume of compressed fluid at high speed.

Another object of my invention is to provide valve mechanism which can be operated 40 at a high speed to control the passage of air to and from a compressor of large volume, so that the greatest possible mechanical and volumetric efficiency will be obtained.

Another object of my invention is to provide a compressor in which the compression 45 chamber is substantially completely emptied of compressed fluid after each compression operation.

Another object of my invention is to provide a single valve element for a compressor 50 which controls the admission of fluid into

the compression chamber, and which also controls the passage of compressed fluid from the compressor chamber.

These and other objects and the invention itself will be more clearly understood from 55 the following detailed description.

In the accompanying drawings—

Fig. 1 is a top plan view of a compressor embodying my invention connected with a self-igniting engine of the solid fuel injection type;

Fig. 2 is a medial vertical section of the same taken on line 2—2 of Fig. 1;

Fig. 3 is a section through the compressor taken on line 3—3 of Fig. 2;

Fig. 4 is a top plan view of the valve sleeve spider;

Fig. 5 is a top plan view of the stationary valve element removed from the cylinder head;

Fig. 6 is a top plan view of the movable valve element; and

Fig. 7 is a sectional view of the same taken on line 7—7 of Fig. 6.

Referring now to the drawings by characters of reference 10 represents the crank case of an explosive engine, which is provided with bearings 11 in which a crank shaft 12 is rotatably mounted. The end of the crank shaft extends through one end of the casing and a fly wheel 13 is secured thereto. An engine cylinder 14 is secured upon the casing, and a piston 15 is adapted to reciprocate within the cylinder, the piston being connected to the crank shaft by a piston rod 16. A pair of oppositely disposed exhaust ports 17 are provided in the cylinder wall located so that they will be covered and uncovered during each reciprocating movement of the piston.

A cylinder head 18 is secured to the upper end of the cylinder, and a fuel injecting device 19 is mounted in a central aperture extending through the head. This device can be of any conventional construction for intermittently supplying a charge of fuel, such as oil, into the explosion chamber which is formed by the top of the cylinder and the cylinder head. A pair of pipes 21 extend from the air compressor and are secured in

open communication with conduits 22 extending through opposite sides of the cylinder head. The conduits terminate in passages diverging outwardly from the inner 5 wall of the cylinder head and on opposite sides thereof. Valves 23 are adapted to be seated against the inner head wall to open and close the passages therein, and the stems 24 are slidably mounted in bearings 25 se- 10 cured through the cylinder head. A coil spring 26 surrounds each of the stems and bears against the engine head, being secured against removal by collars 27 secured to the stem. Rocker arms 28 are secured to shafts 15 75 which are rotatably mounted in bearing brackets 29 secured upon the head, and rods 76 are reciprocated by the cam shaft 30, and are connected to arms 77 secured to the shafts 76.

20 The arms 28 are positioned to engage the upper end of the valve stems and are operated to intermittently move the stems inwardly, thereby unseating the valves to admit compressed air from the pipes 21 into the explosion chamber of the engine. The springs normally tend to maintain the valves in position so that they close the outlet end of the passages within the head.

25 A compressor cylinder 31 is secured upon the top of the crank case in open communication with the interior thereof and adjacent the engine cylinder, and a piston 32 having an annular reduced end portion is mounted to reciprocate therein. A pin 33 is 30 carried by the piston, and a rod 34 is connected to such pin and the crankshaft 12. The cylinder is provided with a plurality of spaced air inlet ports 35 arranged in the same flange around the upper end thereof, 35 and outlet ports 36 are provided in the cylinder wall intermediate the inlet ports and the end of the cylinder. The pipes 21 are secured to the compressor cylinder and provided passages for conducting the compressed air from the outlet ports to the engine head.

40 The compressor cylinder is provided with a closure head 37 which is secured upon the upper end thereof by bolts 38, and an ap- 45 pertured hub 39 extends centrally therefrom into the cylinder. The inner end of the hub terminates in an interiorly extending flange 40 formed to provide a bearing through which a stem 41 is slidably mounted. A 50 hollow packing nut 42 is threaded into the upper end of the apertured hub portion of the head and provides a bearing for the stem 41 which extends therethrough. A station- 55 ary hollow valve element is mounted within the upper end of the compressor cylinder and is positioned in opposed relation to the reciprocating piston 32. The station- 60 ary valve element consists of an annular head 43 of smaller diameter than the cylinder, having a skirt portion 44 extending

therefrom terminating in an outwardly ex- 65 tendsing flange 45 of an outside diameter substantially that of the bore of the cylinder. The flanged portion of the skirt is secured against the cylinder head by screws 70 46. The skirt 44 of the stationary valve element, including the flanged end, is pro- 75 vided with preferably equally spaced slots 47 which extend lengthwise thereof and terminate adjacent the cylinder head portion. An expanding annular ring 48 is mounted in an annular groove in the side wall of the skirt, below the ends of the slots. The inner end of the stem is threaded, and a valve supporting plate, a spider 80 50, is screwed thereon. This plate is pro- 85 vided with a central internally threaded hollow hub portion 51, and also with arms 52 which extend radially from the periph- 90 ery thereof. The arms are arranged so that they will extend through the slots in the skirt portion of the valve element and are provided adjacent their outer ends with bolt holes 53. A slideable cylindrical valve ele- 95 95 ment 54 is positioned within the compressor cylinder, beneath the spider, and is secured against the under side of the arms by bolts 55, which project through the holes 53. The cylindrical movable valve is formed of a diameter to slidably engage the inner wall of the cylinder, and an expanding ring 56 is positioned in an annular recess 57 formed in the outer wall of this valve element. The inner wall of the cylindrical valve element is provided with a plurality of slots 58 which extend lengthwise thereof and terminate ad- 100 jacent the lower end of the skirt.

105 The valve element 54 which is secured to the arbor is of such thickness that it will engage the skirt 44 of the stationary valve element and the inner wall of the cylinder. The valve element 54 is vertically recipro- 110 cated by the movement of the stem 41 to which the spider is secured. The arrangement of the movable valve element is such that it will cover the air inlet ports in the cylinder wall when in its lower position, and when in such position the lower ends of the slots 58 will lie beneath the head of the stationary valve element, thereby establishing communication between the compression chamber beneath the head of the stationary valve element, and the outlet ports 36. Up- 115 120 ward movement of the movable valve element first covers the slots 58 beneath the skirt of the stationary valve element and then uncovers the inlet ports 35. The slots 47 through which the spider arms extend, permit the spider to be reciprocated a limited distance, thereby reciprocating the movable valve element between the cylinder wall and the skirt beneath the cylinder head. The expanding rings 56 and 48 will engage re- 125 spectively the cylinder wall and the inner wall of the movable valve member thereby 130

providing a sealing which materially increases the compression of air within the compression chamber and prevents leakage from the conduits into compression chamber.

The cam shaft 30 is secured in bearing 61 and is positioned above the crankshaft, and a gear 62 is secured to the cam shaft, being driven by a chain 60 from a gear 63 secured 10 to the crank shaft. A plate 64 is secured to the end of the gear 62 and an eccentrically arranged shaft 65 projects therefrom. A rocker arm 66 is pivotally connected to the outer end of the stem 41 and is secured 15 to one end of a shaft 67 which is mounted in a bearing 68 secured to cylinder head. A rocker arm 69 is secured to the other end of the shaft 67 and is pivotally connected to one end of a rod 70. The other end of 20 the rod 70 terminates in a bearing 71 which is loosely secured upon the eccentrically extending shaft 65. The rotation of the crank-shaft causes the eccentric shaft to be rotated with the gear 62, thereby reciprocating the 25 rod 70 and rocking the shaft 67 which reciprocates the stem 41.

The compression chamber is formed within the cylinder, intermediate the head of the stationary valve element and the 30 movable piston. The reduced end of the piston will project within the annular movable valve element, when approaching its extreme upward travel and will extend in close proximity to the head of the stationary valve element when in its extreme upper position, thereby displacing substantially the entire volume of compressed fluid from the compression chamber.

The mechanisms for operating the movable compressor piston and the movable valve element are so arranged, and operated, that as the compressor piston starts down the inlet ports are uncovered by the movable annular valve element, and they remain 40 uncovered until the compression piston is at the bottom of its travel. A fresh supply of air passes into the compression chamber through the ports when uncovered. As the compressor piston starts its upward 45 travel, the inlet ports will be closed by the annular valve element and as the annular valve element moves down the slots in the inner wall thereof will extend below the head of the stationary valve element, permitting the compressed air to pass through 50 passages formed by the slots and the skirt of the stationary valve element into the upper portion of the cylinder and the pipes 21.

It will be observed that the valve elements control both the passage of air into the cylinder, and the passage of compressed air from the compression chamber. The movable valve element and stationary valve element are both of rugged design and are constructed so that compressed air will not

pass therebetween except when one of the valve elements is moved to provide a passage, and the movable valve element is associated with the inner wall of the cylinder so that compressed air can not pass therebetween. The movable valve element and the stationary valve element construction which I have provided will operate at high speeds while air is compressed in large volume without becoming distorted or 70 broken, thereby supplying air under compression necessary for completely scavenging and supercharging self igniting types of engine to produce the power necessary for commercial use. 80

Various changes can be made in the construction described without departing from the spirit of my invention and the scope of the claims.

What I claim is:—

1. In a fluid compressor, a cylinder having inlet ports therein, a piston reciprocable in said cylinder, a stationary valve element within said cylinder, and a reciprocable cylindrical valve element intermediate 90 said stationary element and the inner wall of said cylinder, said reciprocable element controlling the passage of fluid through the inlet ports in said cylinder and cooperating with said stationary element to provide outlet ports for the passage of compressed fluid. 95

2. In a fluid compressor, a cylinder having inlet and outlet ports, a piston reciprocable in said cylinder, a stationary skirted valve element extending within said cylinder, said member having axially extending slots in its skirt portion, a reciprocable stem extending within said cylinder, a spider secured to said stem within said cylinder, said spider having radial arms extending through the slots in said valve skirt, and an annular valve element secured to the arms of said spider, said valve element sealing the space intermediate said stationary valve element 100 and said cylinder and controlling the passage of fluid compressed within said cylinder intermediate said piston and valve elements. 110

3. In a fluid compressor, a cylinder having inlet and outlet ports, a head secured to said cylinder, a piston reciprocable in said cylinder, a hollow valve element, an axially slotted skirt portion for the valve element secured to said head, an annular reciprocable valve element intermediate said stationary element and said cylinder and arranged in leak-proof contact therewith, a spider having arms extending through the slots in said valve skirt, said reciprocable valve element being secured to said arms, and means extending through the head of said cylinder for reciprocating said spider and valve element, said valve elements forming the upper end of the fluid compression chamber, 115 120 125 130

said reciprocable valve element controlling the passage of fluid into said cylinder and controlling the passage of compressed fluid from said chamber.

5 4. In a fluid compressor, a cylinder having inlet ports therein, a piston reciprocable in said cylinder, a stationary valve element within said cylinder, and an annular reciprocable valve element, said reciprocable 10 valve element being in leakproof contact with and intermediate said cylinder and stationary valve element during the compressing movement of said reciprocating piston, said elements cooperating to provide 15 an outlet around said stationary element when the compressing movement of said reciprocating piston is completed.

5. In a fluid compressor, a cylinder having inlet ports therein, a reciprocable compressor piston within said cylinder, a stationary valve element within said cylinder, a reciprocable cylindrical valve element intermediate said stationary valve element and said cylinder, said cylindrical valve element 25 being movable to a position below said stationary element to provide outlet ports for fluid compressed by said piston and to close the inlet ports during the compression of the fluid, and an extension on said piston 30 adapted to extend within said cylindrical valve element and adjacent said stationary valve element at the completion of the compression operation to displace substantially the entire volume of fluid therebetween.

35 6. In a fluid compressor, a cylinder having inlet and outlet ports, a piston reciprocable in said cylinder, a stationary skirted valve element extending within said cylinder, said element having axially extending 40 slots in its skirt portion, a reciprocable stem extending within said cylinder, a support secured to said stem within said cylinder, and an annular valve element secured to the support, said valve element sealing the 45 space intermediate said stationary valve element and said cylinder and controlling the passage of fluid compressed within said cylinder intermediate said piston and valve elements.

50 7. In a fluid compressor, a cylinder having inlet and outlet ports, a head secured to said cylinder, a piston reciprocable in said cylinder, a hollow valve element, a slotted skirt portion for the valve element 55 secured to said head, an annular reciprocable valve element intermediate said stationary element and said cylinder and arranged in leak-proof contact therewith, a support having arms extending through the slots in said valve skirt, said reciprocable valve element being secured to said arms, and means extending through the head of said cylinder for reciprocating said support and valve element, said valve elements forming the 60 upper end of the fluid compression cham- 65

ber, said reciprocable valve element controlling the passage of fluid into said cylinder and controlling the passage of compressed fluid from said chamber.

8. In a fluid compressor, a compression 70 chamber having an inlet port adapted to be closed during the compression operation, a movable member for compressing fluid within said chamber, and a pair of telescopically associated valve elements at the outlet end of said chamber, said valve elements 75 being entirely disposed and within the head portion of the cylinder beyond the cylinder portion swept by the piston, said elements controlling the passage of compressed fluid 80 from said chamber.

9. In a fluid compressor, a cylinder having inlet and outlet ports, a piston reciprocable in the cylinder, a pair of valve elements therefor, one of said elements being 85 stationary and of substantially cylindrical form towards one of its ends and secured at its other end to the head of the cylinder, the valve element being telescoped therefrom within the cylinder, its side walls being 90 spaced from the cylinder walls, the other valve element being annular in form and having outer cylinder wall engaging surfaces and inner surfaces opposing the lateral surfaces of the stationary element, means 95 secured to said annular element to communicate reciprocatory movements thereto from the exterior of the cylinder, said inlet ports being disposed in a lateral side wall of the cylinder so as to be covered by the reciprocatory annular element when moved to its 100 extreme position within the cylinder, the inner walls of the annular element adapted to make close fitting engagement with the lateral walls to prevent fluid from passing 105 longitudinally through the annular element when the annular element is in a less advanced position within the cylinder, said valve elements having their opposing faces 110 relatively so relieved from each other in portions thereof that upon movement of the annular element to its extreme position fluid may pass readily between the lateral walls of the stationary element and the inner walls of the valve element to the outlet portion 115 for the cylinder.

10. In a fluid compressor, a combination with a cylinder having inlet and outlet ports and a piston reciprocable in the cylinder, a valve mechanism disposed in the head portion of the cylinder comprising a stationary valve element and an annular valve element telescoped thereover, said annular element being longitudinally movable and adapted to cover the inlet port of the cylinder in one of its extreme positions and adapted to make close fitting engagement with the stationary element at its inner wall portions to substantially close the head of the cylinder to the egress of fluid therefrom 120 125 130

through its outlet port when in its opposite extreme position, said annular element adapted thereby to permit the discharge of fluid from the cylinder between its inner wall and the outer wall of the stationary element in its first said position, and to prevent such discharge and to permit the admission of fluid through its inlet port in the second said position under the control of the reciprocable said piston. ¹⁰

In testimony whereof I hereunto affix my signature this 17th day of May, 1924.
